UNITED STATES PATENT OFFICE

ERNEST R. SCHULZ, OF CHICAGO, ILLINOIS, ASSIGNOR TO W. H. MINER, INC., OF CHICAGO, ILLINOIS, A CORPORATION OF DELAWARE

END-DOOR CONSTRUCTION FOR RAILWAY CARS AND LOCKING MEANS THEREFOR

Application filed May 31, 1928. Serial No. 281,727.

This invention relates to improvements in end door construction for railway cars and locking means therefor.

In railway car construction, a great many box cars of the automobile type are provided with end doors which form the end walls of the car, two hinged doors being commonly employed at the end of the car, which are locked in closed position by a plurality of locking devices. A well known type of arrangement for locking the doors closed includes a combined door operating and locking mechanism mounted on each door, spaced from the vertical inner edge thereof, this mechanism cooperating with keepers mounted on the door frame above and below the door, and an additional locking means on one of the doors mounted closely adjacent the inner edge of the same and cooperating with locking keepers. In other words, three separate and distinct locking means are employed, thereby greatly increasing the cost of construction. It has generally been considered necessary to employ the plurality of locking devices on the theory that the inner meeting edges of the two doors are too weak to permit of the use of a single, unitary locking means at that point.

It is the principal object of my invention to provide a door construction which overcomes the difficulties pointed out and permits of the use of a single, unitary locking means for both doors which effectively holds the doors closed, thereby greatly simplifying the construction and materially reducing the cost of the same.

A more specific object of the invention is to provide an end door construction for railway cars, and especially box cars of the automobile type, including two hinged doors which together form the end wall of the car when closed, the doors being rigidified along their meeting edges, wherein efficient, unitary locking means of simple design is employed to hold the doors tightly closed, thereby eliminating the use of the multiple locking means hereinbefore referred to, greatly reducing the cost of the end door structure and locking means.

Another object of the invention is to pro-

vide an end door construction of the character indicated, including two hinged doors which form the end wall of the car, wherein the doors are provided with interengaging edge sections, which are reinforced to rigidify the door structure the reinforcing means in effect forming vertically disposed, heavy beam members in the respective doors, which are interlocked against relative displacement when the doors are in closed position, and a unitary locking means is provided for locking said doors in closed relation, the locking means being carried directly by one of said interlocked beam members.

Other and further objects of the invention will more clearly appear from the description and claims hereinafter following.

In the drawings, forming a part of this specification, Figure 1 is an end elevational view of a railway car of the automobile type, illustrating my improvements in connection therewith, the railway car truck and associated parts being omitted in this view. Figure 2 is a vertical, sectional view, corresponding substantially to the line 2-2 of Figure 1. Figures 3 and 4 are horizontal, transverse, sectional views, corresponding respectively to the lines 3-3 and 4-4 of Figure 1. Figure 5 is a vertical, transverse, sectional view, corresponding substantially to the line 5-5 of Figure 3, showing the operating means for the locking mechanism of my improved door construction. And Figure 6 is a horizontal, transverse, sectional view, corresponding substantially to the line 6-6 of Figure 2.

In said drawings, the body of the car is designated generally by the character 10. The body of the car is provided with the usual end sill 11, having the striking casting 12 secured thereto, the striking casting being provided with the usual carry iron 13 which is supported therefrom. The coupler and associated parts of the car are not illustrated in the drawings. The roof of the car is designated by 14, the same being provided with the usual longitudinally extending running board 15. At the top, the end of the car is reinforced by a transversely extending, hollow, metal beam 17 which forms the top member of the door frame. The threshold of the door is in-

dicated by 18 and comprises the usual heavy wooden beam member extending across the car. The car flooring is of the usual type and is indicated by 19.

5 In carrying out my invention, I provide two hinged doors 20 and 21 at the end of the car, the doors being swingingly supported at their vertical outer edges by a plurality of hinge members 22—22 which are secured 10 to the body 10 of the car. The two doors 20 and 21 are of similar design, except as hereinafter pointed out. The main body portion of each door is of the usual construction, comprising a plurality of members 23—23 15 and an outer heavy sheet metal plate 24. As shown in Figure 4, the members 23, forming the door 20, terminate inwardly of the inner edge of the door. The inner edge of the door is reinforced by a vertically disposed I-beam member 25 which is suitably secured to the plate 24. As herein shown, the same is riveted to the plate. The flanges of the I-beam member 25 are arranged in parallel relation to the plane of the door 20 and the 20 outer flange bears directly on the inner side of the plate 24 while the inner flange is in alignment with the inner side of the door. By the arrangement described, the inner edge of the door is provided with a vertically dis- 25 posed channel defined by the flange sections of the I-beam and the central web.

A plurality of heavy blocks 26 are secured to the I-beam member 25 at spaced intervals, as clearly shown in Figure 1. The blocks 26 30 have the opposite sides thereof tapered toward opposite ends, so that the blocks will snugly fit in the channel provided by the I-beam member 25. As shown, the blocks 26 are rigidly secured in the channel of the I-beam member 25, being held by rivets 27 35 extending through the blocks and the flanges of the I-beam.

As shown in Figure 4, the door 21 also has the members 23 terminating an appreciable 40 distance from the inner vertical edge of the door. The inner edge of the door 21 is braced by a pair of I-beam members 28 and 29. The I-beam members 28 and 29 are arranged with the flanges thereof parallel to the plane of the door 21. As shown, the flanges of the 45 two I-beams are arranged in alignment and abut at their inner edges, thereby defining a vertical opening in which the door-locking mechanism is located, as hereinafter more clearly pointed out. The two I-beam members 28 and 29 are rigidly secured to the plate 24 of the door 21 in any well known manner, the same being herein illustrated as riveted to the plate. The door 21 is also provided with the usual weather and spark seal 50 consisting of a vertically disposed, narrow plate 30, secured to the outer side of the door, the same rivets being preferably employed to secure this plate which secure the I-beam members to the plate 24. As shown, the

plate 30 overlaps the door 20 when the doors are closed, thereby effectively sealing the opening between the two doors.

The I-beam member 28 presents a vertical channel at the inner edge of the door, which faces the door 20 when the doors are closed. The channel of the door 21 is defined by the parallel flanges and the web of the I-beam member 28. As shown in Figures 3 and 4, the block members 26 are adapted to engage within the channel of the I-beam member 28 when the doors are in closed relation, so as to interlock the doors and prevent outward movement of the door 20 when the door 21 is in locked position.

70 The two vertically disposed I-beam members 28 and 29 are connected by a vertically disposed strip or plate 31 at the back of the door 21, the strip 31 being secured to the rear flanges of the I-beam members. As herein shown, the plate 31 is secured to the flanges of the I-beam members 28 and 29 by riveting, although the same may be secured by any other well known means.

75 The door-locking mechanism of my improved door construction comprises a pair of vertically slideable shafts or bars 32 and 33, cooperating with upper and lower keepers 34 secured to the body 10 of the car. As herein shown, each keeper 34 comprises a cylindrical body portion having a vertically disposed socket 35 which is adapted to receive the outer end of the corresponding locking bar. Each keeper 34 is provided with a pair of securing lugs 36 by which the same is fixed to the car. The lower keeper 34, as most clearly shown in Figures 2 and 6, is secured to the floor structure of the car by means of rivets, the threshold 18 being recessed to accommodate the keeper, as shown in Figure 6. The threshold 18 is provided with the usual protecting wear plate 37 which is secured at the outer edge to the upper flange of the end sill 11 of the car. As shown, the protecting wear plate 37 extends over the keeper 34 and is provided with an opening in alignment with the socket 35 of the keeper. The keeper 34, which is disposed at the top of the door opening, is arranged within the hollow beam 17 and is provided with securing lugs similar to the lower keeper, by which the same is secured to the horizontal section of the hollow beam 17. The horizontal section of the beam is provided with an opening in alignment with the socket 35 of the upper keeper 34.

80 As clearly illustrated in Figures 3, 4 and 5, the locking bars 32 and 33 are vertically slideable in the opening provided between the two I-beam members 28 and 29. As shown in Figure 2, each bar 32 and 33 comprises an outer end member 38 which has a reduced stem section 39 mounted in a socket at the outer end of the main operating bar member. At the inner end, each operating bar member 85 is provided with a casting 40 having an open-

ing therein which receives the inner end of the bar member, the bar member being secured to the casting 40 by transverse rivets. Each casting 40 has a vertically disposed, 5 upstanding rack member 41 at one side thereof, the rack members 41 of the two castings 40 being oppositely disposed, as most clearly shown in Figure 5.

The locking bars 32 and 33 are operated 10 by means of a handle lever 42 pivotally mounted on a rotary member 43 which is secured to the outer end of a shaft 44 journaled in the door 21, the opposite ends of the shaft being rotatable in bearing members 45—45 15 fixed to the outer and inner sides of the door, respectively. As shown, each bearing member 45 comprises a plate-like section and an inwardly extending, cylindrical sleeve member 46 formed integral therewith, the 20 sleeve member forming the bearing proper. The bearing members 45 are fixed to the outer and inner sides of the door by securing the plate-like sections by any well known means. The shaft 44 carries a pinion 47 25 which engages with the rack members 41 to operate the same.

As will be evident, upon rotation of the shaft 44 in one direction, the cooperating pinion and rack members will effect outward 30 movement of the locking bars 32 and 33, while, when the shaft 44 is rotated in the reverse direction, the operating means will retract the bars 32 and 33. The two locking bars 32 and 33 are properly guided in a vertical direction by a plurality of guide members 48 disposed within the opening between the I-beam members 28 and 29. As shown, 35 each of the guide members 48 is in the form of a block fitting between the I-beam members and secured thereto by cap-screws, as shown in Figure 4, the cap-screws extending through the vertically disposed connecting web of one of the I-beam members. The 40 guide blocks 48 are provided with aligned guide openings 49 which properly guide the locking bars in their movement.

As clearly shown in Figure 1, the operating lever 42 is pivotally connected to the operating member of the shaft 44 in such a manner 45 that the lever will swing about the vertical axis when disposed in the horizontal position shown.

In order to seal the doors, the door member 20 is provided with the usual bracket 50 having an outstanding lug 51 which engages 55 through an opening adjacent the outer end of the handle and is adapted to accommodate the usual car seal.

In closing the doors of my improved construction, the door 20 is first moved to nearly 60 closed position. The door 21 is then swung inwardly until the projecting portions of the blocks 26 on the door 20 enter within the channel at the edge of the door 21. When 65 the outer ends of the blocks 26 have been thus

engaged within the channel of the door 21, the doors are forced tightly closed, thereby bringing the blocks 26 into the interlocked relation with the I-beam member 28 of the door 21, as shown in Figure 3.

With the doors in this position, the operating handle 42 is rotated in a direction to project the extremities of the locking bars 32 and 33 beyond the top and bottom edges of the door. The end portions of the locking bars will thus be engaged within the keepers 34. In order to facilitate the entrance of the extremities of the locking bars into the sockets of the keepers, the extreme end portions of the bars are tapered, as 75 shown. When the locking bars 32 have been interlocked with the keepers 34, the operating handle 42 will be disposed in the horizontal position shown in Figure 1. The handle portion of the locking lever 42 is then engaged over the lug 51 of the bracket 50 and the car seal is applied to the lug in the usual manner.

When the doors are to be opened, the operating lever 42 is rotated in a reverse direction to that hereinbefore described, thereby withdrawing the ends of the locking bars 32 and 33 from the keepers 34.

It will be evident that when the doors are in the closed position with the locking bars 32 and 33 engaged with the keepers 34, the bars will rigidly lock the I-beam members 28 and 29 to the car body proper. It will be evident that the two heavy I-beam members 28 and 29 form rigid reinforcing means for the 95 end structure of the door 21 of exceptionally great strength. It is further pointed out that as the I-beam member 25, which reinforces the inner edge of the door 20, is interlocked with the I-beam member 28 of the 100 door 21 by means of the solid locking blocks 26, a heavy rigid connection is provided within the two door members.

The three I-beam members 25, 28 and 29 together form heavy, vertically disposed, column braces for the end of the car formed by the doors 20 and 21, thus providing a substantially rigid end wall construction when the doors are closed. By the arrangement provided, the single, unitary locking means, 110 comprising the locking bars 32 and 33 associated with the door member 21, is sufficient to lock the parts in fixed relation, preventing outward movement of the doors with respect to the car body, thus eliminating the 115 plurality of locking means heretofore employed in connection with car end doors.

While I have herein shown and described what I consider the preferred manner of carrying out my invention, the same is merely 120 illustrative and I contemplate all changes and modifications which come within the scope of the claims appended hereto.

I claim:

1. In a door construction for railway cars, 130

the combination with a door hinged to the car body, said door being reinforced along the vertical free edge thereof by a pair of beams, each having parallel flange portions connected by a web, said flange portions and web together defining a channel, the flanges of the beams being arranged parallel and edge to edge engagement and the channels defining a vertically disposed chamber; of locking means mounted in said chamber and cooperating with keeper means mounted on the car body for locking the door in closed relation.

2. In an end door construction for railway cars, the combination with a pair of hinged doors extending transversely across one end of the car when closed, to form an end wall member; of means for reinforcing the inner vertical edges of said doors; means carried by the reinforcing means of one of the doors interengaging and interlocking with the reinforcing means of the other door, said last named door having a combined stop and sealing strip at the outer side along the inner edge overlapping the outer face of the cooperating door; a locking device mounted on one of the doors; and fixed keepers on the car body cooperating with said locking device, to lock the doors in closed relation and hold the same against movement with respect to the car body.

3. In an end door construction for railway cars, the combination with a pair of doors hinged to the car body and extending transversely across the end of the car when closed, to form an end wall; of beam members reinforcing the vertical inner edges of said doors, each of said beam members presenting a vertical channel along the inner edge of the corresponding door; a combined stop and sealing strip fixed to the edge of one door and adapted to overlap and engage the edge of the other door; locking means fixed in the channel of said last named door and adapted to enter the channel of the cooperating door to interlock said doors when closed; locking mechanism supported by the beam members of one of said doors; and keepers fixed to the car body, said keepers being engaged by the locking mechanism upon operation of the latter when the doors are in closed position, to effectively lock the doors against movement with respect to the car body.

4. In an end door construction for railway cars, the combination with a pair of doors hinged to the car body at one end thereof, said doors extending transversely across the car at one end thereof when closed and forming the car end wall; of vertically disposed I-beam members reinforcing the vertical inner edges of said doors, each I-beam member having the flanges thereof disposed parallel to the plane of the door on which said beam is mounted, thereby providing open channels at the inner edges of the doors, the channel of

the I-beam member of one of the doors having a block fixed therein and protruding beyond the edge of the door and engageable with the channel of the I-beam member of the other door, to interlock said doors when closed; locking means carried by the I-beam member of one of the doors; and keepers fixed to the car body, cooperating with said locking means when the doors are in closed relation, to lock said doors to the car body against swinging movement.

5. In an end door construction for railway cars, the combination with a pair of doors hinged to the car body, at one end thereof, said doors extending transversely of the car at said end when closed and forming the car end wall; of an I-beam member reinforcing the vertical inner edge of one of said doors; of a pair of adjacent I-beam members reinforcing the inner edge of the other door, the I-beam members of said doors having the flanges thereof disposed parallel to the plane of the door carrying the same; means carried by the I-beam member of one of the doors engaging between the flanges of the outermost I-beam member of the other door, said adjacent I-beam members having door-locking means mounted therebetween; and keepers on the car body above and below said door, said keepers being interengaged with said locking means to hold said doors against movement with respect to the car body.

In witness that I claim the foregoing I have hereunto subscribed my name this 28th day of May, 1928.

ERNEST R. SCHULZ.
